UNITED STATES PATENT OFFICE.

HARRY P. DAVIS, OF PITTSBURG, PENNSYLVANIA, ASSIGNOR TO THE WESTINGHOUSE ELECTRIC AND MANUFACTURING COMPANY, OF SAME PLACE.

ELECTRIC-ARC LAMP.

SPECIFICATION forming part of Letters Patent No. 569,818, dated October 20, 1896.

Application filed January 14, 1895. Serial No. 534,830. (No model.)

To all whom it may concern:

Be it known that I, HARRY P. DAVIS, a citizen of the United States, residing in Pittsburgh, in the county of Allegheny and State 5 of Pennsylvania, have invented a new and useful Improvement in Arc-Lamps, (Case No. 624,) of which the following is a specification.

My invention relates to arc-lamps, and more particularly to methods of and means for 10 controlling the feed of the carbons of such lamps; and it has for its object to provide a means for and method of controlling the feed of arc-lamp carbons which shall automatically and effectively operate to exactly compensate for the consumption of the carbons, 15 and thus insure the production of a light which shall be free from fluctuations and of uniform brilliancy.

The means heretofore most commonly employed for controlling the feeding mechanism 20 of arc-lamps comprised a series-connected coil, which actuated a core or armature for separating the carbons the necessary distance for producing the desired arc and for maintaining such position of the carbons, and a shunt-connected coil for setting the feeding mechanism in operation whenever the separation 25 of the carbons became too great. The objection to such means has been that the feed of the movable carbon was likely to be in excess of that required, the result being that the carbon-points were brought too near together, thus causing a fluctuation in the light, 30 which was objectionable. It is the purpose of my present invention to overcome this objection by insuring a very slight movement 35 of the feeding mechanism at each operation of the same, the operation being repeated until the desired amount of feeding is effected, 40 any excess or overfeeding being thus prevented.

In Figure 1 of the accompanying drawings I have shown a side elevation of my feed-regulating mechanism and the supporting-frame 45 therefor, part of the frame being broken away in order to show the regulating mechanism more clearly. Fig. 2 is a diagram showing a modified arrangement of controlling-coils.

Referring to Fig. 1 of the drawings, 1 is the 50 supporting-frame, and 2 and 3 the lamp-carbons, the carbon 2 in the present instance

being movable and supported by the usual metal bar or rod 4, having the rack-teeth 5 at one edge thereof. Pivotedally supported in the frame at 6 is the frame 7, carrying the 55 usual train of gears 8 9 10, the escapement-wheel 11, and the escapement-lever 12. Supported from one end of the pivoted frame 7 is a dash-pot cylinder 12, the dash-pot piston 14 being pivoted to the frame 1. Connected to the frame 7 at the same side of its pivotal support 6 is one end of a coiled spring 15, the other end of the spring being attached to a nut 16, mounted on a screw 17, fixed to the base of the frame 1. Pivotedally supported 60 from the other end of the frame 7 is a core 18, and surrounding the lower end of this core is the coil 19, in series with the lamp-circuit.

Surrounding the upper end of the core 18 70 is a shunt-connected coil consisting of two reversely-wound sections 20 and 21. Bearing against one side of the carbon-supporting rod 4 is a brush 22, connected by means of a conductor 23 to any desired part of the 75 frame 7 or the feed-regulating mechanism carried thereby. As shown in the drawings, this conductor 23 is connected to the supporting-pivot of the escapement-lever 12. Pivoted to the frame 1, above the movable 80 frame 7, is a stop-bar or lever 24, carrying at its outer end a head 25, an insulating-washer 26 being interposed between this head and its supporting-lever 24. This head 25, which is located in the path of movement of the escapement-lever 12, is connected by means of a conductor 27 to the shunt-coil, the connection being made at the points 28 at which the reversal in winding occurs.

The operation of the invention is as follows: The current entering the lamp, as indicated by the arrows 29, passes through the carbon-supporting rod 4 and the carbons 2 and 3 and series coil 19. The latter draws down the core 18 and the corresponding end 95 of the arm 7, thus elevating the other end of said frame, separating the carbons, and bringing the escapement-lever 12 into engagement with the stop-head 25, thus completing the circuit through the conductor 27 and the shunt-coil. When the distance between the carbons has become sufficiently great to shunt 100

a portion of the current, it will be seen that the portion 21 of the shunt-coil will be short-circuited, the portion 20 only being energized. This energized portion of the coil will serve 5 to raise the core 18 and thus move the escapement-lever 12 away from the stop-head 25 sufficiently to permit a slight movement of the feeding mechanism. The separation of the parts 12 and 25, however, opens the short 10 circuit and current passes by conductor 30 through both sections of the shunt-coil. The section 21 being wound in a reverse direction to that of section 20, the pull of the latter upon the core 18 is opposed by the action of 15 the former, and the frame 7 is rocked to bring the parts 12 and 25 again into engagement, thus locking the escapement of the feeding-train against further movement. If the distance between the carbons is still in excess of 20 normal working conditions, the operation just described will be repeated until the movable carbon has been fed the required amount.

In the modification illustrated in Fig. 2 the normally short-circuited portion 21' of the 25 shunt-coil is located adjacent to the series coil 19' in order to exert a pull in opposition to that of the portion 20' when the short circuit is interrupted. It will be readily seen that the result effected is the same as when 30 the arrangement of coils is that shown in Fig. 1.

It will be readily understood from the description of the apparatus heretofore given that the tension of the spring 15 will be so 35 regulated by means of nut 16 and screw 17 as to slightly overbalance the core 18 when no current is flowing through the lamp. It will also be understood that the dash-pot acts as a retarding means to insure the necessary 40 gradual and regular movement of the frame 7, its operation being in no way different in this connection from that of such devices as ordinarily used.

While I have described specific regulating 45 mechanism, I desire it to be understood that the controlling means described are applicable to other forms of mechanism, and I do not desire to be limited to the specific form shown and described. It will also be understood 50 that the series and shunt spools may occupy different relative positions in the lamp from those shown and described and that a

separate core for each coil may be employed, if desired.

I claim as my invention—

1. The combination with a series coil and a shunt-coil having two sections, one of which is normally short-circuited, of a rocking frame provided at one end with a movable armature or core common to said coils, and a spring 60 and a movement-retarding device connected with the other end of said frame, substantially as described.

2. The combination with a series coil and a shunt-coil having two sections, one of which is normally short-circuited, of a working frame provided at one end with a movable armature or core common to said coils, and a spring 65 and a movement-retarding device connected with the other end of said frame, substantially as described.

3. The combination with the lamp-frame, of the pivoted frame and the gear and escapement mechanism carried thereby, a core or armature and balancing means therefor, a 75 series coil, a shunt-coil having two sections and an insulated stop in the path of movement of the escapement and having a single connection to the two sections of the shunt-coil, substantially as described.

4. The combination with carbon-feed-regulating mechanism, of a series coil, two shunt-coil sections, a core or armature common to 80 said coils and connections whereby one of said shunt-coil sections is short-circuited when the core is actuated by the series coil, substantially as described.

5. The combination with the pivoted frame and the feed-regulating mechanism carried thereby, of a movement-retarding device and 85 a solenoid-core, attached to opposite ends of said frame, a series coil and two shunt-coil sections common to said core and means whereby one of said shunt-coil sections is short-circuited when the core is actuated by the series 90 coil, substantially as described.

In testimony whereof I have hereunto subscribed my name this 10th day of January, A. D. 1895.

HARRY P. DAVIS.
